CLAIM

The ornamental design for a side brush, as shown and described.

DESCRIPTION

FIG. 1 is a front elevation view of a side brush showing our new design;

FIG. 2 is a rear view thereof;

FIG. 3 is a side view thereof;

FIG. 4 is a top view thereof;

FIG. 5 is a bottom view thereof;

FIG. 6 is an overhead perspective view thereof;

FIG. 7 is a bottom perspective view thereof; and,

FIG. 8 is an overhead perspective view thereof with bristles shown.

The broken line showing of side brush is for illustrative purposes only and forms no part of the claimed design.

1 Claim, 8 Drawing Sheets---
